UNITED STATES PATENT OFFICE.

ELMER E. COOK, OF CHICAGO, ILLINOIS.

SWITCH.

1,215,492.

Specification of Letters Patent. Patented Feb. 13, 1917.

Application filed March 23, 1914. Serial No. 826,687.

To all whom it may concern:

Be it known that I, ELMER E. COOK, a citizen of the United States, and a resident of the city of Chicago, county of Cook, and 5 State of Illinois, have invented certain new and useful Improvements in Switches, of which the following is a specification.

My invention relates to switches and more specifically to a switch the operation of 10 which is controlled by a combination lock so as to render operation of the switch impossible without knowledge of the combination of the lock.

The object of my invention is the production 15 of a switch as mentioned which will be of durable and economical construction and efficient in use. Other objects will appear hereinafter.

With these objects in view my invention 20 consists in the combinations and arrangements of parts hereinafter described and claimed.

The invention will be best understood by reference to the accompanying drawings 25 forming a part of this specification, and in which—

Figure 1 is a front elevation, partly in section, of a switch embodying my invention.

Fig. 2 is a section taken on substantially 30 line 2—2 of Fig. 1,

Fig. 3 is a bottom plan view of the switch, the support therefore being shown in section,

Fig. 4 is a section taken on substantially 35 line 4—4 of Fig. 1,

Fig. 5 is a section taken on substantially line 5—5 of Fig. 4, and

Figs. 6 and 7 are fragmentary detail sections taken on substantially lines 6—6 and 40 7—7 respectively of Figs. 5 and 3.

The preferred form of construction as 45 illustrated in the drawing comprises a circular cup-formed body 8 which is mounted in a suitable support 9, being secured to the latter by means of screws 10 which project through a peripheral outwardly projecting flange 11 formed upon said member 8.

Fixed in the body 8 is a circular block 12 50 of insulating material in which are arranged spaced contact points 13 and 13', said contact points being constituted by the heads of screws as shown which are secured in said block by means of nuts 14. Said screws are connected with the line or circuit wires 15 and 15' in conjunction with which the switch is employed, the ends of said wires

being looped around said screws as clearly shown in Fig. 7. A sheet 16 of insulating material is interposed between the under side of block 12 and the bottom of body 8 to prevent contact of the inner ends of said screws or nuts with said body. 60

Arranged upon the front side of the block 12 is a disk 17 circular in form which is fixed in a metallic carrier 18 also of circular form 65 which is rotatably mounted upon the outer or forward end of body 8. Arranged in the underside of the disk 17 is a bar 19 of conducting material which is secured in position by screws 20. The bar 19 is so positioned that through rotation of carrier 18 and hence the disk 17, said bar may be brought into registration with the contact points 13 and 13' to 70 electrically connect the same so as to close the circuit between wires 15 and 15' or, to 75 position said bar out of registration with said contact points as shown in Fig. 5, in which position of said bar, the circuit through the switch will be broken.

The carrier 18 is locked to the body 8 by 80 means of a rearwardly and inwardly extending engaging flange 21 provided at the periphery thereof which is adapted to interlock with outwardly projecting engaging peripheral flanges 22 provided at opposite 85 sides of said body as clearly shown in Figs. 1 and 5. Pins 23 arranged in the peripheral portion of the disk 17 are positioned in the path of one of the engaging flanges 22 and serve as means of limiting the amplitude of 90 oscillation or rotation of said carrier as will be readily understood. The flange 21 is cut away at opposite sides as at 24 so that when it is desired to disconnect or remove the carrier 18, it is only necessary to remove 95 one of the pins 23 and to rotate said carrier to effect registration of the portions 24 with the flanges 22, in which event the flange 21 will be disengaged from said flanges 22 so as to permit of lifting the carrier from position. 100

The carrier 18 and hence the disk 17 are normally locked against rotation with the bar 19 out of registration with the contact points 13 and 13', by means of sectional pins 25 which are loosely mounted in sockets formed as shown in the members 12, 17 and 18. Each of said pins consists of two sections, the arrangement being such that, when one or more of the joints between the 110 contiguous ends of the sections of said pins are out of registration with the joint be-

tween the contiguous surfaces of the members 12 and 17, the latter will be locked against movement, unlocking being effected only through registration of all of the joints in the pins 25 with the joint between said members 12 and 17. Coöoperating with the pins 25 are helical compression springs 26 which normally hold said pins at their outer terminals of movement or in positions in which the joints in some of said pins are in registration with the joint between the members 12 and 17 and in which the joints in the remainder of said pins are out of registration with said joint between said members 12 and 17 as clearly shown in Fig. 5.

Manipulation of said pins in order to effect registration of all of the joints thereof with the joint between the members 12 and 17 is effected by means of depressible members 27 which are loosely mounted in an enlargement 28 formed at the outer side of the carrier 18. The members 27 are notched for engagement with the outer ends of pins 25 and are provided with inclined surfaces 29 so that, upon depression of said members 27, said inclined surfaces, engaging with the adjacent ends of said pins, will cause inward movement of the latter. Helical compression springs 30 coöperate with the members 27 to normally hold the latter at their outer terminals of movement. The arrangement is such that upon depression of the members 27 which coöperate with the pins 28 wherein the joints are out of registration with the joint between the members 12 and 17, said pins will be moved inwardly, through depression of said members 27, to such a position that the joints therein will register with the joint between the members 12 and 17. This being so, when it is desired to unlock the carrier 18 and hence member 17 it is necessary to depress the members 27 which coöperate with the pins 25 whose joints are out of registration with the joint between the members 12 and 17, since if the other of said members 27 are depressed, the remaining pins 25 whose joints are already in registration with the joint between members 12 and 17 will be moved to destroy this registration and thus prevent the desired unlocking. With this arrangement therefore it is necessary that the operator have knowledge as to which members 27 must be operated in order to manipulate the pins 25 which are in non-registering positions.

The switch is especially adapted for use upon automobiles to prevent surreptitious operation thereof, it being clear that with a switch of the construction set forth interposed in the electric ignition system of the automobile engine, it would be impossible for any one except those having knowledge of the combination to unlock the switch in order to close the circuit in which the same

is included. The exteriorly projecting portions of the members 27 are preferably marked, as clearly shown in Fig. 1, so as to aid in learning the combination of the switch and the sockets in which the members 27 are mounted, are cut away at their outer end portions as at 31 in order to prevent scratching or otherwise marring the exteriorly projecting surfaces of said members which would serve to apprise a person as to which of said members should be operated and thus defeat the purpose of the switch. With the sockets in which said members 27 are mounted cut away as mentioned the exterior appearance of all of said members will be the same and therefore will be of no assistance in an effort to ascertain the combination through examination of the exterior surface of the device. The members 27 are locked in position in the bearing member 28 by means of transversely extending pins 32, the upper sides of said members 27 being recessed or cut away as at 33 to accommodate said pins and permit of the desired depressing movement of said members as will be readily understood. Formed upon the outer side of the carrier 18 is a lip 34 adapted to serve as a finger piece to facilitate rotation of said carrier in operating the switch.

While I have illustrated and described the preferred form of construction for carrying my invention into effect, this is capable of variation and modification without departing from the spirit of the invention. For instance, the device may be used in conjunction with more than one circuit it being clear that any number of contact points 13 and connector bars 19 may be arranged in the members 12 and 17. I, therefore, do not wish to be limited to the precise details of construction set forth, but desire to avail myself of such variations and modifications as come within the scope of the appended claims.

Having described my invention what I claim as new and desire to secure by Letters Patent is:

1. A switch comprising in combination, a fixed element, a rotatable element, contact members on said elements adapted to engage when said rotatable element is in operative position, a plurality of movably mounted sectional pins for normally locking said rotatable element in inoperative position, and manually operable means for individually manipulating said pins to unlock said rotatable element, substantially as described.

2. A switch comprising in combination, a fixed element, a rotatable element, contact members on said elements adapted to engage when said rotatable element is in operative position, a plurality of movably mounted sectional pins for normally locking said rotatable element in inoperative position, man-

ually operable means for individually manipulating said pins to unlock said rotatable element and means on said rotatable element engaging between the fingers of the hand 5 manipulating said manually operable means whereby said rotatable element may be readily turned while holding the device in unlocked position, substantially as described.

3. A switch comprising in combination, a 10 fixed element, a rotatable element, contact members on said elements adapted to engage when said rotatable element is in inoperative position; a plurality of sectional pins movably mounted in elongated sockets extending 15 perpendicularly of the joint between and into the contiguous surfaces of said elements, for releasably locking said rotatable element in inoperative position, each of said pins consisting of two sections arranged end to end, said rotatable element being locked in inoperative position by said pins except when the joints between the contiguous ends of said pin sections are in registration with the joint between the contiguous surfaces of 20 said fixed and rotatable elements; spring held manually compressible members extending at substantially right angles to said pins for individually moving the latter, and means on said rotatable member engaging 25 between the fingers of the hand operating said compressible means, substantially as described.

4. A switch comprising in combination, a 30 fixed element, a rotatable element, contact members on said elements adapted to engage when said rotatable element is in inoperative position; a plurality of sectional pins movably mounted in elongated sockets extending 35 perpendicularly of the joint between and into the contiguous surfaces of said elements, for releasably locking said rotatable element in inoperative position, each of said pins consisting of two sections arranged end to end, said rotatable element being locked in 40 inoperative position by said pins except when the joints between the contiguous ends of said pin sections are in registration with the joint between the contiguous surfaces of said fixed and rotatable elements; spring 45 held compressible members having exteriorly projecting portions adapted for manual engagement to individually move said pins, and means on said rotatable member engaging 50 between the fingers of the hand operating said compressible means, substantially as described.

5. In a device of the class described, the 55 combination of a cup-formed circular body; a circular relatively fixed element secured in 60 said body; a second circular relatively movable element rotatably mounted upon said fixed element; a rotatable carrier in which said movable element is fixed; a connection between said carrier and said body locking 65 the same together but permitting of limited

rotary movement of said carrier; spaced contact points on said fixed element; means on said movable element adapted, when the latter is in one position, to register with and electrically connect said contact points; a 70 plurality of sectional pins for normally locking said movable element against rotation; a corresponding number of manually operable means for individually manipulating said pins to unlock said elements, substantially as described. 75

6. In a device of the class described, the combination of a cup-formed circular body closed upon one side and open at the other; a circular relatively fixed element secured in 80 said body adjacent the closed side; a second circular relatively movable element rotatably mounted within said body upon said fixed element adjacent the open side; a carrier to which said movable element is fixed, said carrier closing the open face of said body; interlocking flanges at the peripheries of said carrier and body locking the same together but permitting of limited rotary movement 85 of said carrier; spaced contact points on 90 said fixed element; means on said movable element adapted, when the latter is in one position, to register with and electrically connect said contact points; a plurality of sectional pins for normally locking said 95 movable element against rotation; and manually operable means for manipulating said pins to unlock said element, substantially as described.

7. In a device of the class described, the 100 combination of a cup-formed circular body closed upon one side and open at the other; a relatively fixed element secured in said body adjacent the closed side; a relatively 105 movable element rotatably mounted within said body upon said fixed element adjacent the open side; a carrier to which said movable element is fixed, said carrier closing the open face of said body; interlocking flanges at the peripheries of said carrier and body locking the same together but permitting of limited rotary movement of said carrier, 110 portions of said flanges being cut away to permit of detachment of said carrier when the remaining portions of the flange of each 115 of said parts register with the cut away portions of the flange of the other; spaced contact points on said fixed element; means on said rotatable element adapted, when the latter is in one position, to register with 120 and electrically connect said contact points; a plurality of sectional pins for normally locking said rotatable element against rotation; and manually operable means for manipulating said pins to unlock said element, substantially as described. 125

8. In a device of the class described, the combination of a body; a relatively fixed element secured in said body; a relatively 130 movable element rotatably mounted upon

said fixed element; a carrier in which said movable element is fixed; said carrier having a transverse enlargement upon the outer face thereof, a connection between said carrier and said body locking the same together but permitting of limited rotary movement of said carrier; spaced contact points on said fixed element; means on said rotatable element adapted, when the latter is in one position, to register with and electrically connect said contact points; a plurality of sectional pins movably mounted in elongated slots extending perpendicularly of the joint between and into the contiguous surfaces of said elements and into the said transverse enlargement of the carrier, each of said pins consisting of two sections arranged end to end, said rotatable element being locked in position by said pins except when the joints between the contiguous ends of said pin sections are in registration with the joint between the contiguous surfaces of said fixed and rotatable elements; manually operable plungers mounted in said enlargement on said carrier for manipulating said pins, said plungers projecting from one edge of said enlargement and a radial flange on the face of said carrier adapted to engage between the fingers of the hand operating said plungers, substantially as described.

9. In a device of the kind described, the combination of a fixed element; a rotatably mounted element; spaced contact points on said fixed element; means on said rotatable element adapted, when the latter is in operative position, to register with and electrically connect said contact points, and adapted, when said rotatable element is in inoperative position, to be positioned out of registration with said contact points; a plurality of movably mounted sectional pins for normally locking said rotatable element in inoperative position; and manually operable compressible means having cam surfaces adapted for engagement with said pins whereby the latter may be individually

manipulated to unlock said rotatable element, substantially as described.

10. In a device of the class described, a fixed member and a rotary member, contacts on the adjacent faces of said members, a plurality of locking elements comprising spring pressed split pins, a corresponding number of plungers for operating said pins, said plungers being arranged in said rotary member, and the portions of said rotary element surrounding the outer portions of the plungers being cut away to avoid contacting the outer portions of said plungers, substantially as described. 60

11. A switch comprising a fixed element and a rotatable element, contacts on said elements, a transverse enlargement on the outer face of the rotatable element, a plurality of split pins extending through said elements to lock the same in inoperative position, the ends of said pins extending into said transverse enlargement, and plungers mounted in said enlargement at right angles to said pins and having cam faces engaging the same, substantially as described. 65

12. A switch comprising a fixed element and a rotatable element, contacts on said elements, a transverse enlargement on the outer face of the rotatable element, a plurality of split pins extending through said elements to lock the same in inoperative position, the ends of said pins extending into said transverse enlargement, plungers mounted in said enlargement at right angles 70 to said pins and having cam faces engaging the same, and a flange projecting from the face of said rotatable member adjacent said enlargement and at substantially right angles thereto, as and for the purpose specified. 75 80

In testimony whereof I have signed my name to this specification in the presence of two subscribing witnesses.

ELMER E. COOK.
